Primary Examiner — Darlington Ly*Assistant Examiner* — Katherine A Holbrow(74) *Attorney, Agent, or Firm* — Pearne & Gordon LLP(57) **CLAIM**

The ornamental design for a display screen with graphical user interface, as shown and described.

DESCRIPTION

The FIGURE is a front view of a display screen with graphical user interface.

The broken lines in the drawings illustrate the display screen and portions of the graphical user interface that form no part of the claimed design.
